RAILWAY TRUCK STRUCTURE

Harry M. Pflager, St. Louis, Mo., assignor to General Steel Castings Corporation, Granite City, Ill., a corporation of Delaware

Application March 29, 1934, Serial No. 717,921
Renewed October 2, 1937.

7 Claims. (Cl. 105—2)

This invention relates to streamlining of railway rolling stock and consists in novel truck structure particularly arranged for streamlined vehicles.

5. In order to attain maximum reduction in air resistance to the movement of the vehicle and maximum economy of operation for a given speed, it is necessary that a maximum amount of the outer contour of the vehicle be streamlined.
10. Streamlining the bodies and upper parts of railroad cars and locomotives has been suggested and in a co-pending application Serial No. 703,806, filed December 23, 1933 by the present inventor, is illustrated means contributing substantially to this end by eliminating the pockets between adjacent cars in a train and streamlining the connections.

As far as applicant is aware, no effective effort has been made to streamline the under portions 20 of railway vehicles and in particular the trucks supporting the car bodies from the rails have not been streamlined even though these parts are very irregular in outer contour and obviously produce a great deal of air turbulence and resistance.

The main object of the present invention is to provide a novel streamlined railroad truck which will materially reduce air resistance particularly when the vehicle is traveling at high speed. Another co-pending application Serial No. 717,920, filed of even date therewith by the present inventor, illustrates and claims a novel streamlined railroad car underframe which is particularly adapted for use with trucks embodying 35 the features of the present invention and reference is hereby made to that application.

Another object of the invention is to reduce turbulence in the air beneath the vehicle body and surrounding the trucks which tends to stir up dirt to the discomfort of passengers and to the injury of the equipment.

In the accompanying drawings illustrating the present invention—

Figure 1 is a top view of a truck embodying the invention, half of the streamline sheeting being omitted to disclose the underlying structure.

Figures 2 and 4 are vertical longitudinal sections taken on the corresponding section lines 50 of Figure 1, portions being omitted in Figure 4 to clarify the disclosure.

Figure 3 is a side view of the truck in Figure 1.

Figure 5 is a vertical transverse section taken on the broken line 5—5 of Figure 1.

Figure 6 is an end view of the truck.

Figure 7 is a vertical transverse section taken on the line 7—7 of Figure 8 and illustrating a modification.

Figure 8 is a partial top view of the modified truck.

Figure 9 is an end view of the same.

The truck illustrated utilizes one-piece framing including side frames or wheel pieces 1, transoms 2, and truss-like end members generally indicated at A and formed of vertically spaced transverse members 3 and 3a and longitudinally converging members 4 and 4a. Supported from the transoms 2 by the swing hangers 5 is a spring plank 6 which carries bolster springs 7 mounting the bolster generally indicated at B. Slidable in the pedestals 8 are the usual journal boxes 9 receiving the journal portions of wheeled axles 10. Equalizers 11 paralleling the side frames on each side rest on the journal boxes and support the truck frame through coiled springs 12.

Mounted on the bolster B is the center plate 13 which receives and supports the complementary center plate 14 depending from the body bolster 15. The body underframe center sills 16 are shown upwardly recessed adjacent the center plate 14 to clear the center portion of the truck and are deepened in each direction longitudinally from the center plate 14, the portion at the left or outer end thereof, as indicated in Figure 2, constituting the draft sills 17 provided with the usual draft lugs and guide ribs 18. Extending from side to side and from end to end of the underframe beneath the bolsters 15, the center sills 16, the side sills 19, and the transoms 20, is the sheeting 21 providing a smooth streamlined undersurface therefor. Depending through suitable perforations in the sheeting 21 are the body side bearings 22 for cooperating with the truck side bearings 23 on the ends of the bolster B. This streamlined body underframe is described and claimed in detail in the above-mentioned co-pending application Serial No. 717,920.

To eliminate the numerous irregularities in the outer contour of the truck, the truck is substantially entirely enclosed in sheeting 24 extending around its under, top, side, and end portions, which sheeting provides a smoothly curving and longitudinally tapering streamlined contour. The under portion of the sheeting is supported at each side by ties 25, extending between the inner pedestal jaws 8 on each side beneath the corresponding equalizer 11, and ties 26 connecting the outer pedestal jaws 8 on each side with the transverse 55

members 3a, 4a of the adjacent end structures. At the center, the bottom sheeting is supported by U-shaped brackets 27 secured, respectively, to the transoms 2. 5 The sides of the top portions of the sheeting are elevated as at 28 to clear the truck wheels and brake rigging, and are carried at the sides on the wheel pieces 1 and the ends of the top sheeting are carried upon the end structures. The 10 intermediate portions of the top sheeting are supported and braced by the transverse angles 29. The side portions of the sheeting are bulged outwardly to clear the bolster springs 7 and are braced at the top adjacent the wheel pieces 1 15 by rectangularly disposed angles 30 and 31. At the ends the truck sheeting is supported and braced in the converging hood-shaped contour indicated in Figures 1 and 3 by the triangular end structures.

20 The sheeting is shown as extending continuously without seams on all sides of the truck but this sheeting may be formed of a plurality of plates united by welding or riveting. Openings 32, 34 and 33 in the top portion of the truck sheeting accommodate, respectively, the side bearings 23, the center plate 13, and the brake levers 35 and 35a, the latter being anchored to the bracket 36 projecting from the end member 3. Openings 21a in the underframe sheeting 21 accommodate the brake connections 34b between the truck and the brake equipment inside the enclosed underframe structure. At the bottom the sheeting is perforated as at 37a for the truck wheels 37. The side portions of the sheeting are provided 35 with openings adjacent the wheels and provided with upwardly swinging collapsible doors 38, permitting access to the journal boxes and associated structure. Between the doors 38 is a larger downwardly swinging door 39 for permitting 40 access to the bolster, equalizer springs, etc. The openings for doors 39 are reinforced at the edges by angular doorway framing 40 and 41. The smaller openings for doors 38 are provided along their inner edges with reinforcing strips 42.

45 Projecting from the center of the upper portion of the sheeting and surrounding the opening therein for the center plate 13 is the approximately oval-shaped collar or hollow housing 43 which receives a similarly shaped collar or housing 44 depending from the body underframe around the center bearing 14. These interfitting collars or housings serve to streamline the center connection between the truck and body underframe. This feature is further described and 50 claimed in detail in the above-mentioned co-pending application Serial No. 717,920.

The truck construction in Figures 7 to 9 is similar to that in the form just described except that the truss-like end construction C includes 60 the hood-shaped longitudinally tapering web 45 formed integral therewith. This web 45 is rabbed as at 46 along its inner edges and is joined, preferably by welding, to the top and bottom portions 47 and 48 of the streamline sheeting. The 65 contour of the sheeting and general arrangement of the truck is otherwise the same.

As clearly indicated in the drawings, the truck enclosing casing conforms substantially with the longitudinally smoothly curving lines which produce minimum disturbance of the air through 70 which the vehicle is moving and consequent minimum air resistance to this movement. The casing forms a substantially unbroken enclosure for the truck structure and affords protection against 75 the admission of dirt and water to the journal

boxes, springs, brake rigging, and other relatively moving parts, and tends to maintain the truck in a cleaner condition than is possible with the ordinary truck structure.

The details of the truck framing and equipment illustrated are not essential and the broad features of the invention may be advantageously applied to substantially any kind of truck and will substantially reduce the air resistance offered to movement thereof. Moreover, the general contour of the streamline sheeting may be varied to conform with particular truck and underframe conditions. The exclusive use of all such modifications as come within the scope of the appended claims is contemplated. 15

I claim:

1. In a railway vehicle truck, center bearing elements, a top cover having an aperture for said center bearing elements, and a hollow housing projecting upwardly from said cover around said aperture, said cover and housing being shaped to reduce air resistance of the upper parts of said truck and said center bearing elements. 20

2. A railway vehicle truck constructed and arranged for engaging and pivotally supporting 25 the vehicle body and having streamlined top cover structure independent of the vehicle body and closely following the adjacent contour of the truck, portions of said structure intermediate the sides of the truck being substantially depressed lengthwise of the truck in comparison 30 with the side portions thereof to accommodate irregularities in the under surface of the supported vehicle body underframe.

3. In a railway vehicle truck, spaced axles, 35 wheels and outside journal boxes thereon, a frame including wheel pieces carried on said journal boxes and transverse transoms depressed at their intermediate portions below the level of said wheel pieces, a truck bolster having a body 40 supporting center plate at a level below said wheel pieces, and a closure for said truck including a top plate extending between and carried by said wheel pieces and transoms and extending over said bolster and depressed intermediate 45 said wheel pieces to accommodate body structure resting on said center plate.

4. In a railway vehicle truck, spaced axles, 50 wheels and outside journal boxes thereon, a frame including wheel pieces carried on said journal boxes, a truck bolster, spring supported from said frame and having a body supporting center plate at a level below said wheel pieces, and a closure for said truck including a plate extending between said wheel pieces and depressed 55 intermediate the same to accommodate body structure resting on said center plate.

5. In a railway vehicle truck, spaced axles, 60 wheels and outside journal boxes thereon, a frame including wheel pieces carried on said journal boxes and located below the level of the tops of said wheels, a truck center plate located below said level, and a closure for the truck including a plate between said wheel pieces with raised portions extending over said wheels and 65 depressed portions surrounding said center plate.

6. In a railway vehicle truck arranged for pivotal attachment to a vehicle body, spaced axles, wheels and outside journal boxes thereon, a frame including wheel pieces carried on said 70 journal boxes, a closure for said truck and movable therewith and including a flat bottom plate extending from side to side of the truck adjacent to the bottom of said wheels and apertured for the downward projection of said wheels there- 75

through and also including side plates extending upwardly from said bottom plate and outside of said journal boxes and then inclined upwardly and inwardly for attachment to said wheel pieces and then extending inwardly and downwardly to cover the truck structure and to accommodate portions of the vehicle body beneath the level of the sides of the truck.

7. In a railway vehicle truck arranged for pivotal attachment to a vehicle body, spaced axles, wheels and outside journal boxes thereon, a frame including wheel pieces carried on said journal boxes, a closure for said truck and movable therewith and including a flat bottom plate extending from side to side and from end to end

of the truck adjacent to the bottom of said wheels and apertured for the downward projection of said wheels therethrough and also including side plates extending upwardly from said bottom plate and outside of said journal boxes and then inclined upwardly and inwardly for attachment to said wheel pieces and then extending inwardly and downwardly to cover the truck structure and to accommodate portions of the vehicle body beneath the level of the sides of the truck said closure also including end plates extending upwardly and inwardly for attachment to the ends of said frame.

HARRY M. PFLAGER. 15
